GEORGE KEITH AND WILFRED AMBROSE WHATMOUGH, OF LONDON, ENGLAND.

MEANS FOR CONTROLLING THE SUPPLY OF COMBUSTIBLE MIXTURE TO INTERNAL-COMBUSTION ENGINES.

1,317,709.

Specification of Letters Patent.

Patented Oct. 7, 1919.

Application filed March 29, 1919. Serial No. 286,201.

To all whom it may concern:

Be it known that we, GEORGE KEITH and WILFRED AMBROSE WHATMOUGH, both subjects of the King of the United Kingdom of Great Britain and Ireland, and residing at London, England, have invented a certain new and useful Improvement in Means for Controlling the Supply of Combustible Mixture to Internal-Combustion Engines, of which the following is a specification.

This invention relates to means for controlling the supply of a mixture of fuel and air to internal combustion engines, for example, to engines of automobile vehicles.

One object of the invention is to insure approximately constant quality of the mixture irrespective of the engine speed or load, or of barometric pressure. Another object is to render practicable the employment of combustible gas or vapor from any source; e. g., of vapor produced by evaporation of any suitable fuel.

Yet another object is to render it possible to obtain efficient carburation in engines which are beyond the scope of the ordinary jet or spray carburetors.

Like the construction described in the specification of the co-pending application No. 232421, the present invention involves the provision of a governor operated by pressure functions of the components of the mixture and adapted to maintain a difference of pressure across the gas or vapor supply regulator proportionate to the difference between the pressure at the point of entry of fuel into the induction pipe and the pressure at some other selected point in the induction system.

For convenience it may be assumed, for the purpose of the following explanation of the governing arrangements, that the combustible medium to be admixed with air is available in a gaseous state. This medium is brought to a given pressure (lower than the pressure at which it is supplied) by means of the governor device and thence led past the vapor supply regulator or obturator, adjustable in accordance with the desired proportions constituting the mixture, and induced to flow into the induction pipe or manifold through which is also inspired the air for combustion. The governor device

is provided with a suitable inlet valve controlled by a piston one side of which is exposed to the pressure of the combustible medium, and the other side of which is exposed to the pressure existing at some selected point in the induction system where there is a higher pressure than exists at the point of admission of fuel to the induction pipe. The difference of pressure between these two points will vary with the rate of flow through the induction pipe as the square of the velocity of such flow. The action of the governor is to set up the same difference of pressure across the obturator. As the rate of flow of combustible medium past the obturator varies as the square root of the pressure difference between the two sides of the obturator it follows that the proportion of combustible medium to air will remain constant whatever the demand of the engine.

To control the engine speed, there is provided a throttle valve which may be located in front of or behind the point where the fuel is introduced into the induction pipe, whichever is the more convenient.

It is found in practice that when the engine is running on light loads or idling it may be desirable to enrich the mixture slightly so as to compensate for the inward leakage of air at the valve stems, etc., and also to insure ignition under the lower pressure. This desideratum may be realized by the application of a light spring or other load to the piston, urging the piston in the direction to maintain the valve open.

While a diaphragm governor can be successfully used as described in the specification of application No. 232421 it is found that a piston is the most practical arrangement owing to the limitations imposed by the higher temperatures.

With a suitable piston the influence of weight may be overcome by operating in the horizontal direction, or the piston can be worked in a vertical direction if suitably counterbalanced.

A valve, preferably of a balanced type, is fitted to the piston and so arranged as to open when the piston moves inward, and to close when the piston moves outward, the inner side of the piston being exposed to the pressure of the fuel vapor.

It is desirable that the piston and valve should be readily removable for the purpose of examination and cleaning. For convenience of removal the valve may be of the balanced piston type; but other types of valves may be used.

It will be obvious that with the arrangement described the relative proportion of fuel to air will not be altered with an alteration of the static pressure of the air entering the induction pipe. For this reason the invention is particularly suitable for aeroplane or airship engines, in that the mixture is unaffected by variations of barometric pressure due to varying altitudes, as also in that, when desired, the engines can be supercharged when in higher altitudes without upsetting the quality of the mixture.

Due to the maintenance of constant proportions of the mixture, a higher efficiency in fuel consumption is obtained than is possible with the usual type of jet or spray carburetor. The efficiency is further increased owing to the fact that fuel is supplied in the vaporous state, so that, no matter under what condition the engine is running, a more intimate mixture is effected than is possible where a liquid fuel is merely sprayed or atomized.

It is common knowledge that at low speeds and loads liquid fuel in the ordinary carburetor is not so well atomized as at higher speeds and loads, owing to the lower velocity of air past the fuel jet or jets, and difficulty due to defective atomization increases with the sizes of carburetor and jet so that there is a practical limit to the size of engine that can be efficiently run on the jet-carburetor principle, even where a number of carburetors or jets are used.

The difficulty in question does not arise where the present invention is adopted.

Where the fuel used is in the liquid state, for the purpose of this invention it is necessary to convert it into a vaporous state and maintain it in such vaporous state until it has been mixed with air and the mixture exploded..

For the purpose in view it is essential that the combustible medium should have an approximately constant value, so that it is not admissible to vaporize it by spraying it with air into a hot chamber, as is common practice in the use of fuels with a high boiling point such as paraffin.

As it is intended to utilize the heat of the engine exhaust to vaporize the fuel by boiling it in the absence of air, the form of the vaporizer is very important where there is not a large margin between the exhaust temperature and the boiling point of the last fractions of the fuel used.

The improved vaporizer is preferably constituted by a superposed series of interconnected chambers or cells each comprising

two shallow conical frusta disposed with their bases adjacent and located in a horizontal plane, each chamber being divided into two compartments by a partition formed with marginal perforations. A pipe for the admission of liquid fuel is connected to the uppermost compartment of the vaporizer, the liquid being fed in preferably under pressure and constrained to flow cascade fashion downward, being spread into thin layers on the hot walls and partitions. The resultant vapor is led off preferably by a central pipe from the lower chamber to the admission valve of the governor. The pressure of vapor is approximately equal to the initial pressure of the liquid fuel, so that when the vapor pressure tends to exceed this limit the flow of liquid is retarded or stopped; conversely, if the vapor pressure be reduced, the fuel flows in more rapidly. The vaporizer therefore works on the "flash principle" and is not intended to hold any body of unvaporized fuel.

The vaporizer is housed in an enlargement of the exhaust pipe which is fitted with annular baffles whereby the exhaust products are kept in a state of turbulence and constrained to follow a tortuous course in intimate contact with the conical walls of the vaporizer, which latter, in turn, present a large area exposed to the action of heat.

Such an arrangement not only constitutes a very efficient device for vaporizing fuels of high or low boiling point, but also functions as an effective silencer.

In order to prevent violent oscillations of pressure in the vaporizer, it is advantageous to control the admission of liquid fuel by a throttle valve mechanically connected to the main throttle, so that the amount of fuel admitted will roughly approximate to the demand of the engine. A non-return valve fixed on the fuel pipe also assists to steady the pressure of the vapor in the vaporizer.

Provision is made to prevent establishment of any dangerous vapor pressure due to the eventual boiling of an accidental collection of liquid fuel in the lowest part of the vaporizer by leading a pipe from the said lowest part back to the tank from which the liquid is fed under pressure, such pipe being fitted with a non-return valve and preferably connected to the tank above the level of the liquid fuel. The non-return valve permits fuel to flow from the vaporizer to the tank should the pressure in the vaporizer at any time exceed that in the tank.

An additional safety device may be used to prevent the flow of liquids into the vaporizer when the latter cools owing to stoppage of the engine. The safety device employed consists of a stop valve on the fuel pipe leading to the vaporizer in series with the

throttle valve above referred to, which stop valve is normally kept closed by means of an adjustable spring. The valve spindle is connected to a diaphragm working in a diaphragm chamber; from the diaphragm chamber a pipe connection is taken to the induction pipe of the engine, the arrangement being such that when the engine is running there is sufficient suction on the diaphragm to pull the valve off its seat against the action of the spring, thus permitting fuel to flow to the vaporizer. When the engine stops, as there is no suction in the induction pipe, the valve is closed on its seat by a spring.

As shown in Fig. 7 of the drawings, in lieu of the employment of a governor with valve for controlling the flow of vapor from the vaporizer, the piston or other moving member of the governor may be operatively connected to a cock through which passes liquid fuel that may be led thence for example by way of a braided wire or the like to the uppermost compartment of the vaporizer, the interior of which latter is fully open to the inner face of the piston, and vapor generated in which is conveyed directly from the vaporizer by way of an obturator to the induction pipe system.

In the accompanying drawings which illustrate the invention, Figure 1 shows a complete vaporizer with a piston governor device. Fig. 2 is a sectional detail view, to a larger scale, of the piston governor device. Figs. 3, 4 and 5 are detail views showing one form of valve device for proportioning the supply of liquid fuel approximately to the demand. Fig. 6 shows a device for controlling the delivery of fuel to the vaporizer. Fig. 7 shows an arrangement in which the governor is arranged to control the admission of liquid fuel to the vaporizer.

Referring to Fig. 1, the vaporizer shown is constituted by a series of superposed interconnected chambers or cells A', A², A³, A⁴, comprising pairs of shallow conical frustums disposed with their bases adjacent and located in horizontal planes, each of the chambers A², A³, A⁴ being divided into two compartments by a partition formed with marginal perforations.

A pipe B for the admission of liquid fuel is connected to the uppermost compartment A' of the vaporizer, the liquid being constrained to flow cascade fashion downward and being spread into thin layers on the partitions.

The vapor is preferably drawn off from the lower part of the vaporizer by means of the pipe W. The liquid fuel is supplied to the vaporizer under pressure from the tank B', and is controlled in its passage by the throttle valve h and an automatic valve operable by a diaphragm pin in the chamber p' as hereinafter described.

A pipe connection B² is taken from the lower part of the vaporizer back to the fuel tank B' and is fitted with a non-return valve B³, the function of the pipe B² being to return to the tank any fuel in the vaporizer in the event of the pressure in the vaporizer rising to any appreciable extent above that in the tank B'.

The vaporizer is housed in a preferably cylindrical chamber C, into which leads the exhaust pipe D, and which is fitted with annular baffles E, whereby the exhaust products are constrained to follow a tortuous course in intimate contact with the conical walls of the vaporizer on their way to the exhaust discharge pipe F'.

The governor shown to enlarged scale in Fig. 2 includes a piston G, movable horizontally in a cylindrical chamber G' enclosed in a jacket having free communication with the exhaust gases, said chamber G' having communication with the vaporizer by way of a piston valve which in the arrangement shown consists of a tube U easily slidable axially of the chamber in the movement of the piston G. At one end the tube U is formed with a flange U' embraced between the piston G and a notch plate G'' secured to the piston G and straddling the tube U. V denotes an annular pocket fed from the vaporizer by the pipe W. A row or rows of graduated ports or holes X or a tapered slot in the lateral wall of the tube U serves or serve to admit vapor when in register with the pocket V. The tubular valve U is open at both ends so as to balance itself and to admit pressure to the chamber G'. An additional port or ports Y, as shown in dotted lines, may be provided to connect the outlet with the chamber G', in order to insure equality of pressure. A connection G² is taken from the outer side of the piston G to the induction pipe. Z denotes a drain-pipe for carrying off any condensed fuel which may pass to the outside of the piston G. M denotes a light spring serving to load the piston slightly at lower speeds, the spring urging the piston in the direction to open the ports X of the valve U.

The fuel vapor, after passing through the obturator valve Q, passes downward by means of a pipe a led through the exhaust discharge pipe F' to the throat of the Venturi tube b. A jacket pipe c surrounds the pipe a after it leaves the pipe F' and a jacket d also surrounds the Venturi tube b. A portion of the exhaust gases passes along the jacket c into the jacket d, and may be discharged through holes e in the latter. The usual throttle valve f is fitted between the Venturi tube b forming part of the induction pipe to the engine. At the lower end of the Venturi tube b a float feed carburetor g, or other suitable device, may be fitted for starting purposes, provision be-

ing made for cutting off the supply of fuel from the carbureter when once the engine is running on the vaporizer.

Figs. 3, 4 and 5 illustrate in detail views 5 one form of the valve device shown to small scale in Fig. 1 for proportioning the liquid fuel supply approximately to the demand, combined with a stop cock and check valve. *h* denotes a screw-down valve operated by 10 the quadrant *i*, operatively connected to the throttle valve *f*, as shown in Fig. 1, the quadrant *i* being formed with a number of holes to any one of which is connected a link *j'* operated from the throttle valve mechanism 15 whereby the radial position of the screw-down valve *h* may be adjusted.

There are desirably also fitted in the supply passage a stop valve *h* and a non-return valve *l*. The fuel enters under pressure at 20 the connection *m* and is delivered to the vaporizer from the connection *n*. The function of the non-return valve *l* is to reduce the liability to surging of fuel in the pipe leading to the vaporizer.

25 Fig. 6 shows a diaphragm-operated device of which the diaphragm chamber is indicated at *p'* in Fig. 1, said device being adapted to permit admission of liquid fuel to the vaporizer only while the engine is 30 running. The said device may be fitted to the fuel pipe *B* in series with the valve device *h* just described, and consists of a valve and spindle *o* connected to a diaphragm *p*, or the like, working in a chamber *p'*, an adjustable spring *q* being arranged to keep the valve normally closed. From the diaphragm chamber *p'* a pipe connection *r* is taken to a point in the induction pipe between the throttle valve *f* and the engine, as 35 shown in Fig. 3. The arrangement is such that when the engine is running there is sufficient suction on the diaphragm *p* to pull the valve *o* off its seat against the action of the spring *q*, thus permitting flow of liquid 40 fuel to the vaporizer. When the engine stops, as there is no suction in the induction pipe, the valve *o* is closed on to its seat by 45 the spring *q*.

In the construction shown in Fig. 7, the 50 piston governor is arranged to control the admission of liquid fuel to the vaporizer so as to effect generation of vapor according to the pressure set by the governor in lieu of first generating vapor at a higher pressure and then lowering the pressure by the 55 action of the governor.

In the construction shown in Fig. 7 the fuel enters at the connection *s* and passes through the cock *t*, the lever *t'* of which is 60 operated by means of the piston in such a way as to admit fuel when the piston moves inward and cut off the fuel when the piston moves outward. From the cock *t* the fuel may be led to the vaporizer by a braided wire *w* or the like.

Fig. 7 also shows an arrangement for reevaporating any condensate which may form in the governor chamber, which arrangement may be also used in connection with the system shown in Fig. 3.

70 Between the uppermost chamber *A'* of the vaporizer proper and the governor chamber is an additional chamber *A'*, which may be constructed similarly to the chambers *A*², *A*³, *A*⁴ and which is in communication with the governor chamber *G'* but isolated from the vaporizer chambers.

75 What we claim is:—

1. In combination, a vaporizer, means for supplying liquid hydrocarbon fuel thereto, an induction pipe through which a mixture of fuel and air is sucked to an internal combustion engine, a tubular connection between said vaporizer and said induction pipe, a throttle valve in said induction pipe, a manually adjustable valve or obturator for regulating the delivery of gaseous fuel from said vaporizer to said tubular connection, a chamber, a piston movable in said chamber, a valve automatically operated by said piston and controlling the passage of gaseous fuel from said vaporizer to said tubular connection, and a communicating connection between said induction pipe and said piston chamber whereby the movements of said piston will be controlled by pressure or suction in said induction pipe.

80 2. In combination, a vaporizer, means for supplying liquid hydrocarbon fuel thereto, an induction pipe through which a mixture of fuel and air is sucked to an internal combustion engine, a tubular connection between said vaporizer and said induction pipe, a throttle valve in said induction pipe, a manually adjustable valve or obturator for regulating the delivery of gaseous fuel from 85 said vaporizer to said tubular connection, a chamber, a piston movable in said chamber, a valve automatically operated by said piston and controlling the passage of gaseous fuel from 90 said vaporizer to said tubular connection, and a communicating connection between said induction pipe and said piston chamber whereby the movements of said piston will be controlled by pressure or suction in 95 said induction pipe.

100 3. In combination, a vaporizer, means for supplying liquid hydrocarbon fuel thereto, an induction pipe through which a mixture of fuel and air is sucked to an internal combustion engine, a tubular connection between said vaporizer and said induction pipe, a throttle valve in said induction pipe, a manually adjustable valve or obturator for regulating the delivery of gaseous fuel from 105 said vaporizer to said tubular connection, a chamber, a piston movable in said chamber, a valve automatically operated by said piston and controlling the passage of gaseous fuel from 110 said vaporizer to said tubular connection, a communicating connection between said induction pipe and said piston chamber whereby the movements of said piston will be controlled by pressure or suction in 115 said induction pipe, a spring-pressed fuel inlet controlling valve, a chamber, a diaphragm arranged in said chamber and serving to operate said fuel inlet controlling valve, and a tubular connection between said 120 diaphragm chamber and said induction pipe, at a point in the latter between said throttle valve and the engine.

125 3. In combination, a vaporizer, means for supplying liquid hydrocarbon thereto, an induction pipe through which a mixture of fuel and air is sucked to an internal combustion engine, a tubular connection between said vaporizer and said induction pipe, a throttle valve in said induction pipe, a man-

ually adjustable valve or obturator for regulating the delivery of gaseous fuel from said vaporizer to said tubular connection, a chamber, a piston movable in said chamber, 5 a tubular valve movable with said piston and controlling the passage of gaseous fuel from said vaporizer to said tubular connection, and a communicating connection between said induction pipe and said piston 10 chamber whereby the movements of said piston will be controlled by pressure or suction in said induction pipe.

4. In combination, an induction pipe through which a mixture of fuel and air 15 is sucked to an internal combustion engine, a liquid fuel vaporizer, a tubular connection between said vaporizer and said induction pipe, a valve serving to control communication between said vaporizer and said tubular 20 connection, an obturating member for regulating the delivery of vapor from said tubular connection to said induction pipe, a chamber in communication with said vaporizer, and a piston movable in said chamber, 25 said piston being operatively connected to said valve, and a communicating connection between said induction pipe and said piston chamber whereby said piston will be controlled by pressure or suction of the 30 components of the mixture in said induction pipe.

5. In combination, an induction pipe through which a mixture of fuel and air is sucked to an internal combustion engine, a 35 passage for exhaust gases, a vaporizer in said passage, a tubular connection between said vaporizer and said pipe, said tubular connection extending through said passage, a valve serving to control communication 40 between said vaporizer and said tubular connection, an obturating member for regulating delivery of vapor from said tubular connection to said pipe, a chamber in communication with said vaporizer, a piston 45 movable in said chamber, said piston being operatively connected to said valve, and a communicating connection between induction pipe and said piston chamber whereby said piston will be controlled by pressure 50 or suction of the components of the mixture in said induction pipe.

6. In combination, an engine exhaust pipe, a chamber connected to said pipe, a vaporizer in said chamber, said vaporizer comprising 55 connected cells each consisting of two conical frusta having adjacent bases and an interposed partition having marginal perforations, an induction pipe for air and vapor, a tubular connection between said 60 vaporizer and said induction pipe, a valve regulating the flow of vapor through said tubular connection, and means whereby said valve may be opened or closed more or less according to the pressure or suction in said 65 induction pipe.

7. In combination, an exhaust pipe for products of combustion, a chamber connected to said exhaust pipe and fitted with annular baffles, a vaporizer in said chamber, said vaporizer comprising connected cells alternating with said baffles, an induction pipe for air and vapor, a tubular connection between said vaporizer and said induction pipe, said tubular connection extending through said exhaust pipe, a valve regulating the flow of vapor through said tubular connection, and means whereby said valve may be opened or closed more or less according to the pressure or suction in said induction pipe. 70

8. In combination, an exhaust pipe for products of combustion, a chamber connected to said exhaust pipe, a vaporizer in said chamber, said vaporizer comprising a series of superposed vaporizing cells, a cylinder 85 chamber, a piston movable in said cylinder chamber, a valve operatively connected to said piston, and a vaporizing cell in said first-named chamber isolated from said superposed cells, said last-named cell serving 90 for re-vaporization of condensate which may accumulate in said cylinder chamber, an induction pipe, and a tubular connection between said cylinder chamber and said induction pipe. 95

9. In combination, an induction pipe, a throttle fitted to said pipe, a vaporizer, a tubular connection between said vaporizer and said induction pipe, a governor controlling the passage of vapor through said connection, a tubular connection for admission of liquid fuel to said vaporizer, and a valve member fitted in said second named connection and operatively connected with said throttle. 100

10. In combination, an induction pipe through which a mixture of fuel and air is sucked to an internal combustion engine, a throttle fitted to said pipe, a vaporizer, a tubular connection between said vaporizer 110 and said induction pipe, means for controlling the delivery of vapor through said tubular connection, a tank for supply of fuel to said vaporizer, a tubular connection between said tank and said vaporizer, a non-return valve interposed in said last-named tubular connection, and a return tubular connection from the lower end of said vaporizer to said tank. 115

11. In combination, an induction pipe 120 through which a mixture of fuel and air is sucked to an internal combustion engine, a throttle fitted to said pipe, a source of fuel supply, a tubular connection between said source of fuel supply and said pipe, a manually adjustable obturator for regulating the delivery of fuel from said tubular connection to said pipe, a chamber, a piston, movable in said chamber, a tubular piston valve slide- 125 able in said chamber and operatively con- 130

nected to said piston, and a tubular connection between said induction pipe and said piston chamber whereby the movements of said piston and the valve operated thereby will be controlled by the pressure or suction in said induction pipe.

12. In combination, an induction pipe through which a carbureted mixture of fuel and air is sucked to an internal combustion engine, a vaporizer, means for supplying a liquid fuel to said vaporizer, a valve for automatically controlling the supply of liquid fuel to said vaporizer, a valve for automatically controlling the passage of vapor

from said vaporizer, chambers containing means for operating said valves, and tubular connections between said induction pipe and said chambers whereby said valves will be controlled by the suction or pressure in said induction pipe.

In testimony whereof we have signed our names to this specification in the presence of two subscribing witnesses.
